UNITED STATES PATENT OFFICE.

CLAUDE A. P. TURNER, OF MINNEAPOLIS, MINNESOTA.

CONCRETE BUILDING.

1,025,036.

Specification of Letters Patent.

Patented Apr. 30, 1912.

Application filed January 21, 1910. Serial No. 538,352.

To all whom it may concern:

Be it known that I, CLAUDE A. P. TURNER, of Minneapolis, in the county of Hennepin and in the State of Minnesota, have invented 5 a certain new and useful Improvement in Concrete Buildings; and I do hereby declare that the following is a full, clear, and exact description thereof.

My invention relates to buildings of reinforced concrete, and more particularly to the reinforcement of the floor slabs, and my object is to so reinforce the slab as to diminish or lessen the quantity of material required, while securing a certain desired 15 external form, and to this end my invention consists in the arrangement of reinforcement substantially as hereinafter specified and claimed.

Referring to the accompanying drawings, 20 Figure 1 is a top plan view of a column supported slab having reinforcements embodying my invention; Fig. 2 a vertical section thereof with portions or fragments of the columns shown. Fig. 3 is a top plan view showing the reinforcement for an embodiment of my invention in which no columns are used.

In the embodiment of my invention illustrated in the drawings, there are columns C 30 of reinforced concrete or other construction, and a floor slab S of reinforced concrete. On the under side of the slab are ribs R that extend from column to column, and which may be structural steel beams, or 35 beams of reinforced concrete, and if the latter, as shown they are preferably formed integral with the floor slab S. Extending from one rib to an adjacent one, contiguous to a column, are reinforcing rods or bars f 40 that constitute a sort of head or framework, substantially concentric with the column from which said ribs radiate, and across said reinforcements f, from one column to another, extend belts of parallel rods or bars 45 d, that extend in diagonal directions intersecting at the center of the slab or panel between a group of four columns, and which reduce the bending moment in the central portion of the slab, the action of said belts 50 of rods d, supported as they are by the ribs R, being that of the cantilever. The ribs R besides acting as ordinarily to support the load, are also utilized to support it by belts of rods or bars g that extend across the ribs, 55 preferably at a distance midway between

adjacent columns, said belts of rods g distributing the load to the ribs. Besides the diagonally extending belts of rods or bars d, there are similar belts of rods e, that lie 60 parallel with the ribs R.

In view of the utilization of the ribs R for the support of the reinforcements of the slab, it will be evident that my invention is applicable to a panel supported by beams instead of a floor supported by columns, and the scope of my claims is to be determined in the light of this statement. Such a construction is shown in Fig. 3, in which a single rectangular panel is shown bounded by the four supports R¹. At each 70 of the four corners of the rectangle, the open frames for the belts of diagonal rods d that shorten the diagonal span, are composed of parallel, obliquely arranged rods f¹ that extend between the ribs, and by 75 beam action transmit the slab load from the diagonal belts d to the supports upon which said frame-forming rods f¹ rest. Instead of arranging the rods f in the form of squares, said rods may be given a circular 80 form, the essential matter in this connection being the extension of the rods f across from one rib to an adjacent one or across the corners of the panels as thereby the span in a diagonal direction is shortened, and it is 85 also to be understood that other forms of reinforcements than rods or bars may be employed, without departure from the scope 90 of my invention.

I make no broad claim herein to the system of reinforcement by which a cantilever action for the support of the slab is secured, inasmuch as this and other characteristics of my slab reinforcement are the subject of 95 a pending application, Serial No. 378,444, filed June 1, 1906, in which last named application the broad claims are made.

The fundamental characteristic of my invention can well be pointed out in comparison with the prior art, as found in the patent to Matria No. 634,986 dated Oct. 17, 1899. By the provision of rods cutting across the corners of the panel, I secure the transmission by beam action of the load from the slab to the slab supports, or beams 100 at the sides of the panel, the result being that I increase the bending moment of the beams, for the load is thus transmitted toward the longitudinal center of the side supports or beams. Matria is essentially a sus- 105 110

pended span arrangement, and its effect is to reduce the bending moment of the beams at the sides of the panel, and the load is transmitted into the corners of the panel

5. What I claim is—

1. The combination of a slab of concrete, slab supports arranged to form a rectangular panel of the slab, groups of rods in the slab forming a concentration of rods at and cutting across the corners of the panel and overlapping the supports, series of rods extending diagonally of the panel and supported by said corner rods, and series of rods extending normal to the supports.
2. The combination of a slab of concrete, slab supports arranged to form a rectangular panel of the slab, groups of rods in the same horizontal plane in the slab forming a concentration of rods at and cutting across the corners of the panel and overlapping the supports, series of rods extending diagonally of the panel and supported by said corner rods, and series of rods extending normal to the supports.
3. The combination of a slab of concrete, slab supports arranged to form a rectangular panel of the slab, groups of rods in the lower part of the slab forming a concentration of rods at and cutting across the corners of the panel and overlapping the supports, series of rods extending diagonally of the panel and supported by said corner rods, and series of rods extending normal to the supports.
4. The combination of a slab of concrete, ribs cast integral with the slab arranged to form rectangular panels of the slab, groups of rods in the slab forming a concentration of rods at and cutting across the corners of the panel and overlapping the ribs, a series of rods extending diagonally of the panel and supported by said corner rods, and rods extending normal to the ribs.

5. The combination of a concrete slab, supports therefor arranged in the form of a rectangle, groups of rods in the slab forming a concentration of rods at and cutting across the corners of the rectangle to the contiguous side supports and overlapping the supports, whereby the diagonal span is shortened, and series of rods extending di-

agonally through the slab and supported by said corner rods.

6. The combination of a concrete slab, 5^t supports therefor arranged in the form of a rectangle, groups of rods in the slab forming a concentration of rods at and cutting across the corners of the rectangle to the contiguous side supports and overlapping 60 the supports, whereby the diagonal span is shortened, series of rods extending diagonally through the span and supported by said corner rods, and series of rods extending through the slab directly from side to 65 side thereof.

7. The combination of a slab of concrete, columns, ribs running from column to column in two directions, and forming rectangular panels, and belts of rods running 70 across the corners of the panel and overlapping the ribs, through the slab from side to side of the panel, and diagonally of the panel, there being in the angles a thickness of two belts of the rods that are normal to 75 the ribs, a thickness of two other belts of rods at the corners which make an angle with the ribs, a thickness of at least two belts of rods in the center of the panel and a thickness of one belt of rods at the center 80 of the ribs.

8. The combination of a slab of concrete, columns, ribs running from column to column in two directions, and forming rectangular panels, and belts of rods running 85 across the corners of the panels, through the slab from side to side of the panel and diagonally of the panel and overlapping the ribs, there being in the corners a thickness of two belts of the rods that are normal to 90 the ribs, a thickness of two other belts of rods at the corners which make an angle with the ribs, a thickness of four belts of rods in the center of the panel, a thickness of one belt of rods at the center of the ribs, 95 and carrying rods in the slab crossing areas having a thickness of one belt of rods.

In testimony that I claim the foregoing I have hereunto set my hand.

CLAUDE A. P. TURNER.
